DRAFTING MACHINE

Charles Henry Little, Cleveland Heights, and Charles Hubbard Little, Cleveland, Ohio; Nan Hubbard Little, executrix of said Charles Henry Little, deceased, assignors, by direct and mesne assignments, to Universal Drafting Machine Corporation, Cleveland, Ohio, a corporation of Ohio

Original application September 22, 1944, Serial No. 555,267. Divided and this application November 28, 1945, Serial No. 631,334

12 Claims. (Cl. 33—79)

1

The present invention relates to drafting machines and similar devices comprising a parallel motion mechanism or arm, one end of which is adapted to be secured to a table, drafting board or like device affording a working surface, over which the other end of the arm, provided with some suitable drafting instrument or the like, is adapted to be moved and the instrument carried thereby maintained parallel in successive positions. Parallel motion mechanisms are generally considered to be either of the so-called "parallelogram" type or of the so-called "wheel and band" type, depending upon whether the section or sections thereof are essentially members arranged in parallelogram fashion and pivoted together adjacent to the corners, or wheels held in spaced relation by strut-like members and encircled by a band or bands which maintain a predetermined angular relationship therebetween.

The present invention relates to parallel motion mechanisms and more specifically to a drafting machine or the like comprising a parallel motion mechanism of the wheel and band type, and one of the principal objects is the provision of a novel and improved drafting machine or similar device so constructed and arranged that it will be accurate in operation and will not have the appearance of being bulky and ungainly, and in which the bands and wheels are completely enclosed.

Another object of the invention is the provision of a novel and improved drafting machine or the like of the character referred to having a strut or struts enclosing the wheels and band or bands and so constructed and arranged as to be extremely rigid though comparatively light in weight and adjustable in length for the purpose of tightening or loosening the band.

Another object of the invention is the provision of a novel and improved drafting machine or the like of the character referred to having a strut or struts enclosing the wheels and band or bands and so constructed and arranged as to be readily partially disassembled to afford access to the band or bands for the purpose of assembling or replacing the same.

Another object of the invention is the provision of a novel and improved drafting machine or the like of the character referred to having a band enclosed by the strut, which band is separable for the purpose of facilitating assembly and replacement thereof and comprises means for securing the ends together, so devised and constructed that the ends can be readily connected or disconnected and at least one end will be of minimum thick-

2

ness and maximum flexibility so that the band can be threaded around the assembled wheels although the enclosing strut or member conforms closely to the circumference thereof so as to produce a section of minimum overall width for wheels of any given size.

Another object of the invention is the provision of a novel and improved separable band for a wheel and band type drafting machine or the like, which band comprises means for readily detachably securing the ends thereof together and has at least one end thereof of minimum thickness and maximum flexibility consistent with other requirements so that it can be threaded around assembled wheels although the enclosing strut or member conforms closely to the circumference of the wheels.

The invention resides in certain constructions and combinations and arrangements of parts and further objects and advantages will be apparent to those skilled in the art to which the invention relates from the following description of the preferred embodiment described with reference to the accompanying drawings forming a part of this specification in which similar reference characters designate corresponding parts, and in which

Fig. 1 is a plan view of a drafting machine embodying the present invention;

Fig. 2 is a fragmentary plan view of a portion of the drafting machine shown in Fig. 1;

Fig. 3 is a sectional view, with portions in elevation, approximately on the line 3—3, Fig. 2; and

Fig. 4 is a fragmentary view of the band employed in the drafting machine shown in Fig. 1.

Referring to the drawings, the drafting machine shown therein comprises a two-section parallel motion mechanism or arm of the wheel and band type having one end detachably connected to a drawing board and the other or free end provided with a protractor head adapted to be moved about the drawing board. The parallel motion mechanism or arm comprises two angularly movable sections, each comprising a pair of wheels of equal diameter encircled by a flexible band, which wheels are held in spaced relation by a strut or strut member enclosing the same and the bands. The drafting machine shown preferably comprises counterpoise mechanism for both sections of the parallel motion arm. A suitable counterpoise mechanism is shown and claimed in our copending application Serial No. 555,267 now Patent 2,552,335 granted May 8, 1951,

of which the present application is a division and is not herein shown or described in detail.

The upper or anchor section A of the parallel motion arm comprises wheels encircled by an endless band B. The band wheels are held in spaced relation by an expandable strut C pivotally connected thereto in a manner hereinafter described. The upper band wheel is formed integral with a bracket 12 forming a part of the anchor assembly, which bracket is adapted to engage over the upper edge of a drafting board or the like D and be detachably fixed thereto by a pair of clamp screws.

The anchor strut C comprises yokes or yoke portions or members 22, 23 connected together and held in spaced relation with respect to each other by tubular side portions or members 24, 25. The upper yoke 22 is pivotally connected to a vertical bolt or pin fixed in a boss formed integral with a web of the anchor bracket 12. As shown, the pin is held in position by suitable jamb nuts threaded onto the lower end and the head of the pin is enclosed by a member 31 threaded into a tapped aperture in the center of the yoke 22. The construction is such that the anchor strut C is supported for rotation about the center of the anchor band wheel as an axis. The lower yoke 23 is pivotally connected to the band wheel member at the elbow of the arm for rotation about the center of the lower band wheel as an axis by a bolt or pin to which it is connected by anti-friction bearings.

The strut C is expandable or adjustable in length and separable intermediate the yokes 22, 23 to facilitate assembly and replacement of the band B and for the purpose of tensing the same, etc. To this end the side members 24, 25 comprise tubular sections 34, 35 and 36, 37 fixedly secured to or formed integral with suitable bosses forming a part of the yokes 22, 23, respectively. The adjacent ends of the tubular sections 34, 35 and 36, 37 are normally held in spaced relation with respect to each other and are operatively connected together by tubular nut-like members 40, 41, respectively, the upper ends of which are adapted to engage against shoulders formed on members 42, 43 fixed to the lower ends of the tubular sections 34, 35, respectively, while the other ends thereof are threaded upon the enlarged upper ends of the tubular sections 36, 37. The fact that the ends of the members 36, 37 upon which the members 40, 41 are threaded are enlarged, permits the members 40, 41 to be retracted over the tubular sections by rotating the former in a direction to move them to the left as shown in Figs. 2 and 3 until the threads are disengaged and thereafter the tubular nut members will slide freely on the tubular sections. The tubular nut-like members 40, 41 are normally held in position by jamb nuts 44, 45, respectively.

From the construction described above, it will be apparent that the length of the strut C can be varied by adjusting or rotating the tubular nut-like members 40, 41 after first loosening the jamb nuts 44, 45, and that when the nut-like members 40, 41 are retracted from their normal position, the flexible band B will be loose on the wheels 10 and 11 with a considerable portion thereof exposed, thus facilitating assembly or replacement of the band. Since the side members 24, 25 are of tubular form, the band B must be threaded through the strut and about the wheels and is, therefore, made separable at one point. As shown in Figs. 3 and 4, one end of the band B is provided with two spring members or arms

46 located at opposite sides of the band proper and riveted thereto. The free ends of the arms 46 normally receive the other end of the band proper which has a small rivet or pin 47 extending therethrough, the projecting portions of which engage within suitable apertures formed in the ends of the members 46. The construction affords a simple and convenient means for hooking the ends of the band together and produces a band one end of which is extremely flexible and of minimum thickness, thus reducing to a minimum the clearance necessary between the wheels and yokes to thread the band about the wheels. Obviously a band of any suitable construction may be employed.

The protractor section F of the parallel motion arm is similar in construction and will not be described in detail. It comprises a pair of equal diameter band wheels encircled by a band similar in construction to the band B previously described and held in spaced relation by a strut G comprising yokes 52, 53 located at the elbow and drafting or protractor head, respectively, of the drafting machine and held apart by side members 54, 55 similar in construction to the side members 24, 25 previously described. The band wheel at the elbow of the parallel motion arm is formed integral with the lower portion of the band wheel member of the anchor section A located at the elbow of the arm and the band wheel at the drafting head is formed integral with the holding ring of the drafting or protractor head. The yoke 52 of the protractor strut G is supported by an anti-friction bearing for rotation about a pivot lower end of the bolt or pin at the elbow of the arm and the band wheel at the drafting head is rotatably supported by an anti-friction bearing in the yoke 53.

The protractor or drafting head shown and referred to generally by the reference character H comprises a ruler assembly J including the normally rotatable element K of the protractor proper, and one or more rulers 59. In addition, the protractor head comprises a normally stationary protractor element which stationary protractor element cooperates with the rotatable protractor element to indicate the angular position of the ruler or rulers with respect to some given base or reference line. The ruler assembly J is adapted to be indexed relative to the stationary protractor element assembly L by an index mechanism located, except for the projecting part of the thumb piece 61 within and underneath the hand knob 62 also forming a part of the ruler assembly. As shown the stationary protractor element L is provided with a graduated circle and the rotatable protractor element with a reference or "zero" line or vernier. Alternatively the graduated circle may be placed on the rotatable protractor element and the vernier on the stationary protractor element, etc. Alternatively any desired appropriate type of drafting or protractor head may be employed with the improved parallel motion mechanism or arm of the present invention.

From the foregoing description of the preferred embodiment of the invention, it will be apparent that the objects heretofore enumerated and others have been accomplished and that there has been provided a novel and improved drafting machine or the like comprising a parallel motion mechanism of the wheel and band type which is light in weight, rigid in construction and operation and of limited size and wherein the bands are completely enclosed but can be readily re-

placed and the tension thereof adjusted as desired.

While the preferred embodiments of the invention have been described with considerable detail, alternative constructions may be employed. The invention is not limited to the particular construction shown and described and it is our intention to cover hereby all adaptations, modifications and uses thereof which come within the practice of those skilled in the art to which the invention relates and within the spirit and scope of the appended claims.

Having thus described our invention, what we claim is:

1. In a drafting machine or the like, a pair of band wheels, a band encircling said wheels and comprising a strip or ribbon having its ends connected together between said wheels, a strut pivotally associated with said wheels for maintaining the same in spaced relation with the band under tension and having two aligned tubular side members enclosing portions of said band between said wheels including portions adjacent said connected ends, and a sleeve-like member surrounding a portion of said band and movable along one of said tubular side members and movable to and from the other of said side members to afford access to said ends of said band.

2. In a drafting machine or the like, a pair of band wheels, a band encircling said wheels and comprising a strip or ribbon having its ends detachably connected together between said wheels, and a strut pivotally associated with said wheels for maintaining the same in spaced relation with the band under tension and comprising two aligned separable tubular side members enclosing portions of said band adjacent said detachably connected ends, a sleeve member surrounding a portion of said band and movable along one of said tubular members into and out of engagement with the other of said tubular members to afford access to said detachably connected ends of said band.

3. In a drafting machine or the like, a pair of band wheels, a band encircling said wheels and comprising a strip or ribbon having its ends connected together, and a strut pivotally associated with said wheels for maintaining the same in spaced relation with the band under tension and comprising two aligned separable tubular side members enclosing portions of said band adjacent its connected ends, and a sleeve-like member surrounding a portion of said band and movable along one of said tubular side members in one direction into engagement with the other of said tubular side members to separate said side members to tense said band, and movable in the opposite direction from said other tubular side member to afford access to said ends of said band.

4. In a drafting machine or the like, a pair of band wheels, a band encircling said wheels and comprising a strip or ribbon having its ends thereof detachably connected together between said wheels, detachable securing means attaching said ends together, and a strut pivotally associated with said wheels for maintaining the same in spaced relation with the band under tension and comprising two aligned separable tubular side members enclosing portions of said band adjacent to said securing means, a sleeve-like nut member adopted to be threaded on one of said tubular side members and movable relative to the other of said tubular side members in one direction along said one tubular side

member to afford access to said securing means and in the opposite direction along said one tubular side member to move against said second tubular member to tense said band.

5. In a strut adapted to form a part of a drafting machine or the like of the wheel and band type and hold the band wheels thereof in spaced relation while encircled by an endless band, two aligned separable tubular side members adapted to enclose portions of the band extending between the wheels, and a sleeve member surrounding a portion of said band and movable along one of said tubular side members into and out of engagement with the other tubular member to separate said tubular members and to afford access to said band, respectively.

6. In a strut for a drafting machine or the like having a pair of band wheels and a band encircling said wheels, the combination of two aligned separable tubular side members enclosing portions of said band between said wheels, and a sleeve-like member movable in opposite directions along one of said tubular side members and adapted to slidably telescope with the other of said tubular members when moved in one direction and to be withdrawn with said other tubular member when moved in the other direction to afford access to said band.

7. In a strut adapted to form a part of a drafting machine or the like of the wheel and band type and hold the band wheels thereof in spaced relation while encircled by a band, the combination of two aligned tubular side members adapted to enclose portions of the band extending between the wheels and a sleeve-like member adjustably positioned on one of said tubular side members and movable relative thereto in one direction to engage the other of said tubular side members to urge said tubular members from one another to extend the strut and tense said band, and movable in the opposite direction and from said other tubular member to afford access to said band.

8. In a drafting machine or the like having a pair of band wheels encircled by a band, and a strut pivotally associated with said wheels for maintaining the same in spaced relation with the band under tension, said strut comprising two aligned tubular members enclosing portions of said band between said wheels, a sleeve interconnecting said tubular members and having one end portion slidably telescoped with one of said tubular members and having a part abutting said one member to urge it in a longitudinal direction, and means for adjustably attaching the other end portion of said sleeve to the other of said members to adjustably position said sleeve along said other member for selectively spacing said members by said sleeve.

9. In a drafting machine or the like having a pair of band wheels encircled by a band, and a strut pivotally associated with said wheels for maintaining the same in spaced relation with the band under tension, said strut comprising two aligned tubular members enclosing portions of said band between said wheels, a sleeve for interconnecting said tubular members and having one end portion threaded on the end of one of said tubular members and the opposite end portion slidably telescoped with the other of said tubular members and having a part abutting said other tubular member to urge it in a longitudinal direction when said sleeve is threaded outwardly on said one tubular member, said

sleeve having its inside diameter intermediate its ends greater than the diameter of the threaded end of said one tubular member whereby said sleeve can be moved onto said one tubular member and away from said other tubular member to expose a portion of said band.

10. In a drafting machine or the like having a pair of band wheels encircled by a band, and a strut pivotally associated with said wheels for maintaining the same in spaced relation with the band tension, said strut comprising two aligned tubular members enclosing portions of said band between said wheels, a sleeve interconnecting said tubular members and having one end portion slidably telescoped with one of said tubular members, said one tubular member having an abutment thereon engaged by the end of said sleeve, and means for adjustably connecting the other end of said sleeve to the other of said members to adjustably position said sleeve along said other member to maintain said tubular members separated.

11. In a drafting machine or the like having a pair of band wheels encircled by a band and a strut pivotally associated with said wheels for maintaining the same in spaced relation with the band under tension, said strut including two parallel tubular sections enclosing parallel reaches of said band, each section comprising two aligned tubular members, a sleeve interconnecting the spaced tubular members and having one end slidably telescoped with one of said members and having a part abutting said one member to urge it in a longitudinal direction, and means for adjustably connecting the other end of said sleeve to the other of said members to adjustably position said sleeve along said other member for selectively spacing said members by said sleeve.

12. In a drafting machine or the like having a pair of band wheels, a strut pivotally associated
